UNITED STATES PATENT OFFICE.

FREEMAN A. TABER, OF BOSTON, MASSACHUSETTS.

LAMP.

SPECIFICATION forming part of Letters Patent No. 236,108, dated December 28, 1880.

Application filed September 3, 1880. (No model.)

To all whom it may concern:

Be it known that I, FREEMAN A. TABER, a citizen of the United States, residing at Boston, in the county of Suffolk and State of Massachusetts, have invented certain new and useful Improvements in Lamps; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention, in the main, is based upon a class of fountain oil-lamps shown and described in Letters Patent of the United States issued to myself on the 15th day of April, 1879, in which the oil-fount, or the same and its inclosing-case, is combined with the hanger which suspends the lamp from the ceiling in such manner that the fount and case are susceptible of vertical sliding movements to and fro of the hanger and with respect to the shades or globes of the lamp, which are stationary with the hanger, by which means the fount and burner may be lowered and separated from the globes and ready access had to the burners and the filling-orifice of the fount when trimming, lighting, or filling of the lamp is necessary.

In my present lamp I employ an oil-fount extending bodily to and connecting directly with the wick-reservoirs, in lieu of a common central fount supplying by means of branch pipes the various burners, as in my patent above named, and I employ in place of said fount a shell which is a counterfeit of it, and serves to conceal the spring-bolts which secure the movable portions of the lamp, the oil-fount passing through such shell, and with the burners, which are attached to it, being removable from the case which contains it, and the whole being substantially as hereinafter described. I also employ as a novel feature in my present improvements a tube disposed within the wick-reservoir, which supports the burner and contains the wick, such tube extending nearly from top to bottom of the said reservoir, and serving to protect the oil therein from the disturbance and agitation due to the swinging of the lamp when applied to railway-cars or steam-

ers, thereby preventing the fluctuations of the light, which are now of common occurrence from the movements of the body of oil in the main reservoir acting upon that contained in the wick-reservoir.

The drawings accompanying this specification represent, in Figure 1, a longitudinal vertical section of a portion of a hanging lamp made in accordance with my invention; in Fig. 2, a vertical cross-section through the oil-reservoir, and Fig. 3 a vertical section through the hanger.

In said drawings, A represents the suspensory or hanger by which the lamp is suspended from the ceiling of a railway-car or other apartment, or saloon of a steamship, this hanger being of yoke form, and the lower extremities of its arms terminating in horizontal ring-sleeves B B, which serve to uphold the globes or shades C C which surmount the burners.

Centrally of the lower part of the hanger I add a horizontal circular cap or disk, D, which serves not only as a cover to the counterfeit oil-fount, but as a guide to vertical rods a a, erected upon the shell or case E containing the oil-fount proper, E', which rods slide in passages b b in said disk D, and by means of which the oil-fount and burners may be lowered and separated from the shades or globes, thereby enabling ready access to be had to such fount and burners when trimming, cleaning, or lighting the wicks is necessary or the fount needs replenishing with oil. Should it be desirable to remove the oil-reservoir altogether, it may be lifted out of its inclosing-case when the latter is lowered.

To uphold the oil-fount and burner and the case which contains them when in their highest position, I add to the opposite sides of the interior of the cylindrical central portion, F, of the case E, which contains the oil-fount E', spring-latches G G, the lower ends of which are secured to the lower part of the case, while their upper ends are formed with catches or hooks b' b' to engage the upper part of the disk D, orifices c c being formed in such disk to permit of passage of the ends of the latches.

The central cylindrical portion, F, of the case E resembles an oil-fount, but is in reality merely a hollow cylinder, while the ends of the case extend laterally from it, and terminate each in a vertical tubular case, H, which con-

stitutes a receiver for the wick-reservoir I, in which each end of the oil-fount E' terminates.

The oil-fount E' is a continuous vessel from end to end, and carries at each extremity a burner, J, such burner being secured to the top of a vertical tubular wick-reservoir, K, in which each end of the fount terminates, and which communicates directly with the interior of the fount.

10 L in the drawings represents a vertical tube disposed within each wick-reservoir I, this tube being of slightly less diameter than the interior of the reservoir to provide a shallow annular chamber, d, between the two, and being 15 erected upon and secured to the bottom of the said reservoir, the height of this tube or shield L being such as to extend above the openings leading from the oil-fount to the reservoir, as shown in Fig. 1 of the drawings. The tube or 20 shield L serves to break the force of the swaying body of oil in the fount, thereby preventing the fluctuation of the light, which now frequently occurs from the agitation of the body of oil contained in the main fount acting upon 25 that contained in the wick-reservoir. To prevent to a certain extent swaying of the body of oil in the fount itself, I add to the interior central portion of the latter a pendent tube, N, which is secured at its upper end to the 30 mouth of the filling-orifice O of the fount, a shallow space, e, intervening between the lower end of this tube and the bottom of the fount to permit of filling of the latter.

Rings or handles *ff*, placed equidistant from 35 the center of the fount, may be added to the top of the latter to enable it to be readily lifted from its case should occasion require.

I claim—

1. The combination, substantially as herein-before set forth, of the stationary hanger and 40 its cap, the oil-fount shell or receiver provided with a cylindrical portion and movable up and down in the hanger, so that said cylindrical portion may be covered by said cap or uncovered, according to the direction of movement, 45 and the oil-fount removable from said shell or receiver.

2. The combination of the hanger carrying the shades or globes, the shell or case E, carried by and movable up and down in said 50 hanger, locking devices for securing the shell in its raised position, and the oil-fount E', removable from shell E and provided at opposite ends with wick-reservoirs, substantially as hereinbefore shown and set forth.

3. The combination, with shell E and removable fount E', of the wick-reservoir K and the tubular shield L therein, extending up to or above the point in the side of the reservoir at which the latter communicates with the 60 fount, substantially as herein shown and set forth.

4. The removable oil-fount having a tubular central tube, and carrying reservoirs at its ends provided with internal tubular shields 65 which extend up from the bottom of the wick-reservoirs to or above the height of the lateral communicating openings between the fount and the wick-reservoirs.

In testimony whereof I affix my signature 70 in presence of two witnesses.

FREEMAN A. TABER.
